UNITED STATES PATENT OFFICE.

PREScott M. HULBERT, OF DETROIT, MICHIGAN.

ELECTRIC HEATER.

1,319,002.

Specification of Letters Patent.

Patented Oct. 14, 1919.

Application filed October 31, 1910, Serial No. 589,938. Renewed January 15, 1919. Serial No. 271,337.

To all whom it may concern:

Be it known that I, PREScott M. HULBERT, a citizen of the United States of America, residing at Detroit, in the county of Wayne 5 and State of Michigan, have invented certain new and useful Improvements in Electric Heaters, of which the following is a specification, reference being had therein to the accompanying drawings.

10 The invention relates to electric heaters and consists first, in the novel construction of a protected heating unit and the method of forming the same, second, in the application of this heating unit to the construction 15 of an electric furnace capable of developing high temperatures, and by the use of an untransformed commercial electrical current.

Heretofore, various constructions of carbon electrical resistances have been employed for developing heat, but have proven unsatisfactory for various causes among which are first, the combustible nature of the material when heated beyond the temperature of ignition, second, the varying resistance under different conditions which render it difficult to control the heat and current consumption, third, the necessity for using a large current volume at low pressure which requires the transformation of the 30 commercial currents available, fourth, the difficulty in fashioning the material into the desired form and spaced dimensions with the requisite mechanical strength and proper electrical resistance. For these and various 35 other reasons carbon heating units are objectionable and unsatisfactory.

It is the object of the present invention, first, to obtain a method of constructing carbon heating units of any desired form and 40 dimensions, and to impart to each unit an independently selected and predetermined electrical resistance according to the heating effect desired, second, to protect this unit from destruction through combustion and 45 from excessive heat and at the same time to develop therewith high temperatures, third, to place the unit in an accessible position so that the work may be conveniently inserted into and removed from the zone of high 50 heat, fourth, to provide an effective heat insulation and to guard against loss of heat through convection when the heating chamber is open. These and other objects are 55 accomplished by the construction as herein-after described.

In the drawings,—

Figures 1 to 4 are diagrammatic perspective views illustrating the method of constructing the carbon resistance element;

Figs. 5 and 6 are similar views showing a 60 modified construction;

Fig. 7 is a vertical central section through a protected unit designed for furnace construction;

Figs. 8 and 9 are respectively longitudinal 65 and cross section through a modified form of protected unit;

Fig. 10 is a section through another modification;

Figs. 11, 12, and 13 show modified 70 constructions of resistance elements;

Fig. 14 is a view similar to Fig. 7 of a modified furnace construction;

Fig. 15 is an elevation of the slotted unit having extended dead ends; 75

Fig. 16 is a perspective view of sectional units designed for a rectangular furnace construction;

Fig. 17 is a horizontal section showing the 80 connection of the terminals to the resistance; and Fig. 18 is a horizontal section of the resistance after the slitting and before removing the core.

My improved heating unit is constructed 85 of substantially pure carbon and thus differs from constructions in which mixtures of carbon and inert refractory materials have been employed. Preferably I employ graphitic carbon of that variety which has been artificially graphitized. 90

One of the features of my invention is the method of fashioning this material by which a high electrical resistance may be imparted to a body of any dimensions and of any desired form, the method being as follows: 95

A body of graphite of selected form and dimensions is first fashioned preferably by machining. For instance, a solid block of graphite A is cut into a tube or cylinder B and is then slotted to increase the length 100 and decrease the section of the conductor for the electrical current. This slitting may be performed in various ways, but as shown in Fig. 3, the tube or cylinder is slotted alternately from opposite ends C, C', the slits being uniformly spaced and the series extending completely around the cylinder, with terminal portions D, D' of somewhat greater section. In slitting, the depth of the cut is less than the thickness of the wall 110

of the cylinder and consequently all of the sections between the slits are tied together, and the rigidity of the cylinder is not impaired. The slotted cylinder is then engaged 5 with a suitable chuck or holder E and is bored in a lathe or other tool to remove the solid inner shell F, leaving the sections between the slits free from each other with the exception of the connection portions at 10 opposite ends. As a result a zig zag body is formed, the resistance of which is determined by the number of slits, and the selection of this resistance is not limited by reason of the original size or dimensions of the 15 tubular body, but may be varied as predetermined.

In place of slitting the body D longitudinally, it may be cut into a spiral form as shown at G Fig. 5, leaving the same uncut 20 inner shell, and subsequently boring through this shell as shown in Fig. 6.

An electrical resistance formed as above described may be practically constructed suitable for use with available commercial 25 currents without transformation to reduce the voltage. If however, such a resistance were to be heated above the ignition point and exposed to the atmosphere, it would soon be destroyed by combustion and even 30 where protected by embedding in a body of refractory material the same result will follow after a greater length of time. In fact it has been found practically impossible to protect such a resistance by any method 35 heretofore employed. I have overcome this difficulty in several alternative ways, first, by protecting the resistance with a case formed of the same material but suitably spaced for insulation, second, by inclosing 40 the resistance with a different material of a refractory nature and in which it is hermetically sealed so as to prevent any access of free oxygen to the carbon while under high heat and at the same time permitting free 45 transmission of the heat to the work, third, by limiting the temperature developed in the resistance to a point below that of ignition.

As shown in Fig. 7, the first of the above 50 referred to constructions is employed, that is the inclosing of the resistance in a case of the same or similar carbonaceous material, the detail construction being as follows:

The protecting case is formed of an upper 55 and a lower section H, H' each being provided with outer and inner annular walls H² and H³. The inner wall surrounds the chamber H⁴ in which the work is to be placed while the annular space between the 60 walls is sufficient to admit the slotted cylindrical resistance I, with a clearance space on all sides thereof. This resistance is supported on a refractory insulator bed, such 65 for instance as calcined magnesium oxid J which separates the ends of the resistance

from contact with the base ring H' of the case and also preferably affords side supports to hold the upper portion of the resistance from contact with the case. The terminal connections for the resistance pass 70 out from the case through an extension thereof which as shown comprises the lateral hollow extension H⁵ upon the upper section H and the registering downwardly extending tubular portion H⁶ on the section H'. Within these extensions are arranged the 75 terminal conductors I' which are suitably fashioned to be maintained out of contact with the case and to extend from a bearing on the resistance I to the outlet end of the tube H⁶. The terminals are rigidly attached to the resistance by a mechanical joint and as shown this consists of a screw I² of the same material as the terminals and the resistance and clamping the same together. 80 The lower end of each terminal is suitably supported in insulating material as indicated at J'. This may be the same as that employed at J, or if desired a less refractory material as it will not be subjected to 85 high a degree of heat.

With the construction thus far described the case for the resistance and its connections will effectually protect the latter from oxidization as it is evident that before oxygen 90 from the atmosphere can obtain access to the heated resistance it must pass through the case, and in so doing will become neutralized by union with the carbon forming the carbon monoxide gas. This gas will have no detrimental effect upon the resistance whatever 95 temperature the latter may be heated to. It is however, necessary to protect the case from destruction and also to provide suitable heat insulation to prevent waste of 100 current, and a means of access for the insertion and removal of the work from the heated chamber. This I accomplish by the use of an external gas-tight jacket which is 105 lined with a refractory heat insulating material and is open at the bottom in registration with the chamber H⁴ to permit access to the latter. This case will maintain a non- 110 oxidizing atmosphere about the resistance and its protecting case for the reason that the heated gases within the case being under 115 higher vapor tension, will not commingle by convection with the external atmosphere beneath. In other words, the tendency is for the gases to rise, and where the cold atmosphere beneath the case is forced upward through the orifice in the bottom by any disturbance, it will be expelled without commingling by the greater tension of the inner atmosphere.

It is evident from the above description that the outer jacket if gas-tight above the base, will prevent any exchange of gases other than that by diffusion, which is too slow to produce a detrimental effect. Upon 120 125 130

the first heating of the resistance the oxygen in the atmosphere within the jacket will attack the carbon of the case H but as soon as the supply is exhausted or neutralized, further oxidation is prevented by the gaseous atmosphere thus developed. Thus the resistance is guarded from injury as long as the protecting case is preserved and the life of the latter depends on the amount of free oxygen or oxidizing gases contained within the jacket each time that it is heated. The amount of gas in an empty jacket would produce but a slight oxidizing effect, but where refractory insulating material is placed within the jacket as a lining this may operate as a holder for oxidizing gases, particularly so where there are any carbonates present. I therefore preferably provide a protection for the case H formed of carbonaceous material preferably pulverized charcoal. This may be placed to completely surround the case H without any danger of short circuiting the electric circuit, and it is evident that any oxidizing gas penetrating this material will be neutralized before it can reach the carbon case. By the term envelop as employed in the claims is meant anything that envelops, whether it be a gas, solid or combination of elements. As shown in detail in Fig. 7, K is a base ring supported on a suitable standard K' and apertured at K² for access to the heater. Upon this ring is mounted the case H supported by the tubular extensions H⁶, the supports being held up a sufficient distance to diminish loss of heat in a downward direction to the base. The jacket L is also supported on the ring K and consists of an outer gas-proof wall L' preferably formed of metal, and an inner wall L² which may be formed of a more refractory material. The inner wall is spaced from the jacket H a sufficient distance for forming the charcoal containing chamber which preferably connects with a tube L³ extending upward to the top of the jacket and provided with a detachable gas-tight cap L⁴. This permits of renewing the supply of charcoal when necessary. Between the walls L² and L' is placed a suitable heat insulating material, such as infusorial earth, calcined magnesium oxid or other refractory bodies which are poor heat conductors.

The terminals I' are connected with metallic conductors M which are coupled by any suitable means (not shown) with the electric circuits. The work is inserted and withdrawn from the heating chamber H⁴ by suitable means that shown consisting of a refractory supporting plate N connected to a vertically extending shank N' also of refractory material, and coupled with a slide N² upon the standard K'. The shank N' serves to raise the support N into the heating chamber, while the slide N² operated by

a foot-lever or other suitable means (not shown) will raise and lower the shank N'.

In place of the construction shown in Fig. 7 I may employ a protection for the resistance I shown in Figs. 8 and 9, of the following construction:

I is the slotted resistance the same as shown in Fig. 7, which is surrounded by a case O of a refractory insulating material, such as calcined magnesium oxid or fused silica. This case may be produced by a method forming no part of the present invention but consisting in the integration of the refractory material which is first in a comminuted state, and in which the resistance is embedded. The integration is effected by high heat and is carried to such an extent as to form not only a case but a gas-proof seal. Thus the surface of the body is either completely fused or is glazed by a more fusible material to form the seal.

Still another modification is shown in Fig. 10 in which the bare resistance I is supported on a refractory insulator base such as H', is surrounded by a jacket L having an inner lining L⁵ of a refractory material impervious to the gas and around which the heat insulating material P is placed. With this construction the work is inserted and removed from the jacket as in Fig. 7, and upon heating the resistance is exposed to the oxygen within the heating chamber, but as soon as this is neutralized, will be protected by the lining L⁵ from further oxidation. The life of such a resistance is necessarily limited but may be maintained for a sufficient length of time to be of practical service.

Various modifications in the construction of the resistance may be made, as shown in Figs. 11 to 16. Thus in Fig. 11 a flat plate Q of graphite is slotted and is provided with terminal connections Q' mechanically engaging the same. In Fig. 12 an arch-shaped construction is formed by a slotted segmental plate R, and in Fig. 13 a slotted dome-shaped construction S is shown. All of these modifications may be employed as elements in any of the protected constructions referred to and illustrated in Figs. 7, 8 and 10. Fig. 14 illustrates another modification which may be employed for a heater of limited length of life and consists of a spiral resistance T surrounding a muffle or inner case T' and itself surrounded by a protecting case formed of alternate layers of carbonaceous material and refractory insulating material T² and T³. The spiral is connected at opposite ends to terminal connections T⁴ insulated from each other by the layers T³ of insulating material. There is also an outer jacket T⁵ with a heat insulating lining T⁶ but not necessarily a gas-tight construction. With this modification the length of life is limited to the time in which the carbon layers of the outer case remain un-

consumed, but during this period the resistance will be protected and a high degree of heat may be developed therein.

My invention is applicable to various uses, but is particularly adapted for the development of high heats above the fusing point of metallic resistances generally employed. Thus in the construction shown in Fig. 7 a sufficiently high heat may be developed to fuse platinum silica and other bodies having even a higher fusing point, without any detrimental action upon the furnace itself. In fact there is no limit to the degree of the heat except that at which the carbon vaporizes, as the refractory insulating base may be carried down to a point where it is out of the zone of highest heat. Thus as shown in Fig. 15, the resistance may be formed of a slotted cylinder U having dead ends U' extending downward below the poles of the electric current and supported on an insulating base U². An intensely high heat may therefore be developed within the portions of the graphite forming the electric circuit, but the temperature of the lower ends of the bars U' will be sufficiently low to avoid destroying of the insulating material.

With the construction as described in use when the current is passed through the slotted resistance, heat will be developed first in the resistance and then by radiation will pass to the carbon case which will rise in temperature at near the same speed as the resistance itself. The outer wall of the case being in contact with the charcoal body will impart heat to the latter through conduction, and as the ignition point of the charcoal is lower than that of the graphite, the former will first be attacked by the oxygen of the atmosphere within the inclosing jacket, this will rapidly convert the free oxygen as well as any carbon dioxid which may be liberated from the heat insulating material into carbon monoxid, which being fully saturated with carbon will not attack the graphite resistance or its case. Thus the resistance will be protected by the gaseous envelop which together with the carbon walls of the case effectually excludes any free oxygen. During the period that the furnace is under heat, the high vapor tension within the heating chamber and the upper portion of the jacket, will prevent any exchange of atmosphere by convection, and furthermore, the moisture which is always present in the charcoal and heat insulating material, where the furnace is used intermittently, will cause a constant slow generation of carbon monoxid gas and hydrogen by decomposition of the water vapor in contact with the heated charcoal. This gas will pass out the orifice in the base of the jacket where it will be burned, and any oxygen carried into the furnace by the introduction or withdrawal of work therefrom,

will be consumed by uniting with this carbon monoxid gas. Whenever it is necessary the cap L⁴ may be removed and the supply of charcoal surrounding the graphite case renewed. The charcoal is held from falling out at the base by a retainer wall V of refractory material but at any time when it is desirable to remove the charcoal or any ash accumulating at the bottom of the case, the outer jacket may be lifted off, thereby providing access to all the parts inclosed therein.

While I have shown the resistance with only two terminal connections, it is obvious that intermediate terminals can be extended from the case to permit of varying the resistance for different voltages and to produce different heating effects.

What I claim as my invention is:

1. An electrical heating unit, comprising a carbon resistor, a carbon shield for protecting said resistor from atmospheric convection, and means for rendering the atmosphere reactively neutral to carbon at contact temperature.

2. An electrical heating unit, comprising an integral carbon body slotted to increase the resistance thereof, a carbon case for protecting said resistor from atmospheric convection, an insulator support for said resistor in said case maintained at relatively high temperature, and means for maintaining an atmosphere containing carbon and oxygen reactively neutral to the carbon at contact temperature.

3. An electrical heating unit, comprising an integral carbon resistor body slotted to increase the resistance thereof, a carbon case for inclosing said resistor spaced therefrom to maintain atmospheric insulation, and a refractory insulator support for said resistor within said case.

4. An electrical heating unit, comprising an integral carbon resistor body slotted to increase the resistance thereof, a carbon case inclosing said resistor and spaced therefrom to maintain atmospheric insulation, a refractory insulation for supporting said resistor within said case, and means external to said case for developing and maintaining an atmosphere reactively neutral to carbon at contact temperature.

5. An electrical heating unit, comprising an integral carbon body vertically slotted to form a series of zigzag sections, a carbon case inclosing said resistor and spaced therefrom to maintain atmospheric insulation, a refractory insulator support for said resistor within said case, engaging the ends of said sections, and means external to the carbon case for developing and maintaining an atmosphere reactively neutral to carbon at the temperature of contact with said resistor.

6. An electrical heating unit comprising a fashioned in contour slotted carbon body,

and a protecting gas-tight case therefor forming a chamber open to the external atmosphere at a point below the slotted portion of said body.

5 7. An electrical heating unit comprising a fashioned in contour slotted carbon body, a surrounding gas-proof jacket therefor forming a chamber open at the bottom, a heat-insulating lining for said jacket, and means 10 within said jacket for developing and maintaining a non-oxidizing gaseous envelop protecting said body.

8. An electrical heating unit comprising a fashioned in contour slotted carbon body, a surrounding gas-proof jacket forming a chamber open to the external atmosphere, a refractory heat-insulating lining to said jacket, and a carbon body surrounding said slotted body and insulated therefrom forming 20 an oxygen-proof shield therefor.

9. An electrical heating unit comprising a fashioned in contour slotted carbon body, a surrounding gas-proof case therefor, means for developing a non-oxidizing atmosphere 25 within said case enveloping said body, and a refractory insulating support for said body within said case.

10. An electrical heating unit comprising a fashioned in contour slotted carbon body 30 forming the resistance element, a carbon case surrounding said element and spaced therefrom, a refractory insulator support for said resistance element within said case, terminal connections and an extension of said 35 case from which said terminals pass out of the zone of heat.

11. An electrical heating unit comprising a fashioned in contour slotted carbon body of annular form, constituting the resistance 40 element, an annular carbon case inclosing said body, a refractory insulator support for the resistance within said case, and a gas-proof jacket surrounding said case forming a chamber opened to the external atmosphere 45 within said annular case.

12. An electrical heating unit comprising a vertically slotted carbon body constituting the resistance element, and a refractory electrical insulator support for the lower ends 50 of the sections which are between the slits of said body.

13. An electrical heating unit comprising

a slotted carbon body, and an insulator support for the ends of the sections of said 55 slotted body.

14. An electrical heating unit comprising a slotted carbon body constituting the resistance element, means for maintaining a non-oxidizing gaseous atmosphere about said element, and a refractory insulator support for 60 said element engaging the ends of the sections thereof.

15. An electrical heating unit comprising a slotted carbon body surrounding a work 65 chamber and constituting the resistance element, a gas-proof jacket surrounding said resistance element and forming a chamber opened at the bottom in registration with said work chamber, means for maintaining 70 a non-oxidizing gas within said jacket and chamber, and a refractory insulator support for the ends of the slotted sections of said body within said jacket.

16. An electrical heating unit comprising 75 a vertically slotted carbon body constituting the resistance element, a refractory insulator support for the lower ends of the slotted section, and carbon terminal connections mechanically joined to the ends of said slotted body leading outward therefrom.

17. An electrical heating unit, comprising a combustible resistor, a case surrounding said resistor having an opening therein for the insertion and withdrawal of work, 85 and means for maintaining a non-oxidizing gas surrounding said resistor and between the same and said opening in the case.

18. An electrical heating unit, comprising a combustible resistor arranged to form 90 adjacent thereto a work chamber, a case surrounding said resistor having an opening in its bottom providing access to said work chamber for the introduction and withdrawal of work, thermal insulation interposed between said resistor and case, and means for maintaining a non-oxidizing gas within said work chamber around said resistor, and between the same and the opening 95 in said case.

In testimony whereof I affix my signature in presence of two witnesses.

PRESCOTT M. HULBERT.
